OSCILLATING CONTACT DEVICE FOR PERIODICAL VARIATION OF ELECTRIC CURRENT CONDITIONS

Johan Torsten Westin, Amal, Sweden, assignor to Aktiebolaget Hakanssons Industrier, Amal, Sweden, a corporation of Sweden

Application July 30, 1946, Serial No. 687,057
In Sweden August 1, 1945

5 Claims. (Cl. 200—90)

1

This invention relates to oscillating contact devices for periodical variation of electric current conditions and more particularly to improvements in a self-acting electromagnetic switch device for providing current impulses spaced by relatively long time intervals, during which the current is broken.

In self-acting switch devices of the above character it is a well known principle to utilize an oscillating body having a low periodicity. Such devices are used, for instance, for electric fences. In order to attain this action, however, it is necessary for the oscillating body to have a comparatively large mass and for the oscillations to be brought about by means of comparatively light spring means.

This principle involves disadvantages from the points of view of construction and reliability of operation, in that it entails a relatively bulky, heavy, expensive and easily damaged apparatus. Current variations of a frequency less than that of the oscillating body itself cannot possibly be obtained by means of this known apparatus.

Accordingly it is an important object of this invention to make provision for the frequency of the current variation to be to a large extent independent of the number of periods per unit time of the contact device proper, which number can be given a suitable value. With this arrangement the above disadvantages are eliminated. This is highly valuable, particularly in contact devices for such low current pulse numbers as are necessary, for instance, for electric fences, signal lamps, output limiters and similar apparatus.

More specifically it is an object of the invention to provide a contact device including a swinging, preferably oscillating, body, which is actuated by electromagnetic or mechanical means.

The main feature of the invention resides in that the contacts of the apparatus are arranged in such a manner in relation to the oscillating body that the circuit containing said contacts remains open while said body (or pendulum) is oscillating and is closed again as said body comes to rest or nearly so.

The aforesaid and other objects I attain by the constructional forms shown in the accompanying drawings, wherein, for the purpose of illustration only, there are shown a number of preferred embodiments of my invention, and wherein:

Figure 1 is a diagrammatic view illustrating in neutral position a contact device comprising a pendulum body and pendulum contacts arranged adjacent each side thereof.

2

Figures 1a, 1b, and 1c show the contact device of Fig. 1 in operation.

Figure 2 is a diagrammatic side view, partly in section, illustrating in inoperative position a contact device according to the invention in association with an electromagnet.

Figures 2a and 2b show the contact device of Figure 2 in operative position.

Figure 3 is a side elevation of a modified form 10 of the contact device of Fig. 2.

Figure 4 illustrates a further modified embodiment of the invention, and Figure 4a shows this embodiment in operation.

Figures 5 and 6 illustrate two further modified 15 embodiments of the invention.

Figs. 1, 1a, 1b, and 1c are intended to illustrate the principle of the invention. The reference numeral 1 designates a central pendulum being, for instance, a metal leaf spring, which is fixedly supported at one end, the other end thereof being free to oscillate. The numerals 2 and 3, respectively, indicate two pendulum members contacting the central pendulum 1 on opposite sides thereof (Fig. 1), said lateral pendulum members 20 having preferably equal flyweight masses and numbers of periods in relation to each other but of less values in relation to the central pendulum. The contact pendulum members are connected to a source of current 4, and a load 5 is series connected in the circuit. At the fixed supporting points the pendulum contacts 2, 3 are insulated from each other and from the central pendulum 1 by means of insulation pieces 6.

If the central pendulum 1 is given an electro- 35 magnetic or mechanical power impulse (indicated by the arrow in Fig. 1a), which it is itself, of course, capable of transferring directly or indirectly if connected as a self-acting switch, the central pendulum will carry the contact pendulum 2 with it but will separate from the contact pendulum 3. This causes the circuit to be opened. When the central pendulum 1 has completed a quarter of a period and begins to move in the reverse direction it will separate from the contact pendulum 2 due to the lower periodicity of the latter. As soon as the central pendulum has 40 passed its initial position it will bring with it the contact pendulum 3 without being retarded to such an extent as to permit the contact pendulum 2 to catch up. Thus the circuit will still be open (Fig. 1b). On the next reversal of the central pendulum 1 it will first separate from contact pendulum 3 and then meet and bring with it contact pendulum 2 (Fig. 1c), whereupon the 45 course of events will be repeated. Thus, with 50 55

suitably proportioned pendulum members the circuit is maintained open until the oscillations are damped out or substantially damped out. Thereafter the central pendulum will receive a new impulse, begin to oscillate and keep the circuit open until the oscillations are again damped out, etc.

Fig. 2 illustrates a contact device associated with an electromagnet and preferably adapted for application to an electric fence. The electromagnet is provided with double windings 7, 8 and thus acts as a transformer. The iron core 9 of the electromagnet is provided with an air gap 10, in the vicinity of which the magnetic lines of force are deflected. The pendulum body or bob 11 of the central pendulum 1 is made of soft iron and acts as an armature for the electromagnet. In this case only one of the contacts, 2a, is placed on a pendulum arm 12, whereas the other, 3a, is secured to the free end 13 of a spring metal strip 14, the opposite end of which and the corresponding ends of central pendulum 1 and contact arm 12 are secured to the iron core 9 by means of a screw 15. Adjacent the gap 10 the metal strip 14 is formed with an S-shaped double bend 16, whose portion 17 to the right of the gap 10 contacts the core 9. At their fixed ends central pendulum 1, pendulum arm 12 and metal strip 14 are insulated from each other by means of insulation pieces 6.

When current is supplied through lead 18, pendulum arm 12, contacts 2a and 3a, metal strip 14, grounded leads 19 and 20, primary winding 8 and lead 21, the armature 11 is operated, so that it will powerfully impact the bend 16 (Fig. 2a). Thereupon the free end 13 is moved upwardly throwing the contact 2a of the pendulum arm 12 away from itself resulting in an opening of the circuit at that point. Then the central pendulum 1 will spring back past its original position to meet the pendulum arm 12 having now a downward movement (Fig. 2b). The continued operation will proceed substantially as described in connection with Figs. 1 to 1c. Not until the oscillations of the central pendulum begin to die out the contact 2a will again abut contact 3a, whereby the circuit is closed again and the operating cycle is repeated. Each time a current impulse passes through the primary winding 8, a higher voltage impulse is induced in the secondary winding 7 which is connected to a fence wire through conductor 22. Reference numeral 23 indicates a capacitor.

The embodiment of Fig. 3 corresponds to a substantial degree to the contact device illustrated in Figs. 2 to 2b and differs therefrom, practically, only in that the contact 3a is changed from the end of the spring metal strip 14 to the iron core 9, from which it is insulated by means of an insulation piece 6.

As the armature 11 of the central pendulum 1 is operated and thereupon impacts the bend 16 of metal strip 14 the free end 13 thereof will spring upwardly and impact pendulum arm 12. Thus the contact 2a is forcibly separated from the contact 3a, whereby the circuit is opened. The continued succession of events will agree with that described above.

Fig. 4 illustrates a contact device which makes it possible to obtain longer time intervals between the current impulses than is the case as regards the arrangements of Figs. 1 to 3, inclusive. In the contact arrangement according to Fig. 4 both contacts 2a and 3a are secured to pendulum arms 12a and 14a, respectively, said arms being provided with extensions 24 and 25,

respectively, extended past said contacts. A fixed stop 26 insulated from the iron core 9 by means of an insulation piece 6 projects into the space between the extensions. The pendulum arm 12a has a magnet armature 27, and the armature of central pendulum 1 is divided into two portions 11a and 11b.

When current is supplied the magnetic field lines deflected at the gap 10 will pass through armature portion 11a, magnet armature 27 and armature portion 11b and back to the iron core. This results in a simultaneous attraction of armatures 11a and 11b, and 27. Then the deflection of pendulum arm 12a is limited by extension part 24 being stopped by stop 26 (Fig. 4a). The central pendulum 1, however, is permitted to perform a greater deflection, in which it carries with it the pendulum arm 14a. When, owing to the fact that contacts 2a and 3a are brought out of engagement with each other, the circuit is opened the central pendulum 1 will spring back past its initial position carrying with it the pendulum arm 12a. Thereafter the operating cycle will proceed as before.

A further advantageous embodiment of the invention is illustrated in Fig. 5. This arrangement departs from the two foregoing in that the contact spring 13 (14a) is omitted and the mode of operation aimed at is obtained by providing the central pendulum 1 with a contact 2b which, as the primary circuit is closed, and, as a result thereof, the armature 11 is operated by the electromagnet 9, closes the secondary circuit momentarily by rapidly impacting a contact 3b connected in that circuit and secured to an insulation piece 6 fixed to the core 9. When the pendulum 1 is in its neutral position the primary circuit is closed by a contact 2a provided on spring 12a and a contact 3a secured to the core 9 through the medium of an insulation piece 6. The impact of contact 2b on contact 3b causes a slight vibration in the core 9, whereby the primary circuit is opened at the contacts 2a, 3a, which are, in the manner already described, kept apart by the oscillating pendulum 1 until the oscillations thereof are damped out or nearly damped out.

A further and very advantageous embodiment of the invention is illustrated in Fig. 6. In this figure two braces or other securing means for the spring members are indicated at 28, members 29 being insulation pieces, 30 and 31, respectively, two leaf springs, 32 a magnet armature secured to leaf spring 33; members 33, 34 and 35, 36, respectively, are two pairs of contacts, 37 a relatively rigid bell crank, 38 a leaf spring supporting the latter, 39 a second armature carried by bell crank 37 and spring 38; 40 and 41 are connections for the secondary winding, 42 and 43 are connections for the primary winding, 44 and 45 are terminals for a source of current, and 46 is a terminal for a load device, such as an electric fence. The elements referred to are interconnected and associated in a manner to operate as follows:

If a source of current is connected across the terminals 44 and 45 the primary circuit is closed. Thereby the core 9 is magnetized and operates the armatures 32 and 39. The motion of armature 39 is transferred by bell crank 37 to contact 34 so that the latter is rapidly moved to the right (according to the figure) until contact 35 engages contact 36 and is instantly stopped. In the course of its movement the contact 34 will press and slide on the contact 33, which is forced upwards due to the inclination of the contact surfaces

relative to the direction of movement of contact 34. When the contact 34 is stopped, the contact 33 will continue to move upwards, the contact surfaces will be separated and the primary circuit will be opened. Then the magnetic flux will disappear, whereby a higher voltage impulse is induced in the secondary winding. This impulse is supplied through closed contacts 35 and 36 to terminal 46 and thence to the load device. When the flux vanishes the armatures 32 and 39 are de-energized and the biased springs 30 and 38, respectively, act to move the same in a direction opposite to that caused by the energization thereof. The motion of armature 39 is transferred by bell crank 37 to the contacts 34 and 35, which are rapidly returned to their original positions. The contacts 35 and 36 are separated and the distance between the contacts 33 and 34 is increased. On account of the butt impact of the bell crank 37 against transformer core 9 on reaching its initial position the movement of bell crank 37 will cease practically instantaneously. Owing to the freely oscillating pendulum armature 32 the contact 33 is in the manner described prevented from engaging the contact 34 and thereby causing the primary circuit to close until the fly-weight energy stored in the pendulum 32 is substantially consumed. The pair of contacts 35, 36 serves to shorten the time during which secondary voltage can be applied to terminal 46.

The embodiments hereinabove described and illustrated in the accompanying drawings are, of course, to be considered merely as examples, and the different parts of the arrangement are susceptible of being varied in numerous ways without departing from the scope of the invention.

What I claim and desire to secure by Letters Patent is:

1. An improved contact device comprising in combination, an oscillatable member, electromagnetic means for periodically actuating said member, a source of electric current, an oscillatably mounted contact, a second fixed contact cooperating therewith, circuit means, and a circuit cut-off means comprising a spring metal strip, said strip having an S-shaped bend therein at a point opposite said oscillating member and the free outer end of said strip being adapted to be located close to the pendulum arm of said oscillatable contact when the latter is at rest, said bend having a knee thereof engaging a fixed support, said oscillatable member engaging said strip adjacent the knee of said S-shaped bend, and said movable member being adapted during each period of its movement to actuate said contact members in such a manner that said member, once set in motion, will act to open said contacts only after having stored up a predetermined amount of energy, and to thereafter maintain said contacts open until said energy stored up in said member is substantially consumed after having performed a plurality of oscillations.

2. An improved contact device comprising in combination, an electromagnetic means, an oscillatable member forming an armature of said means, an oscillatably mounted contact, a second contact co-operating therewith, circuit means, and a circuit opening means comprising a spring metal strip having an S-shaped bend therein, said bend having a knee thereof engaging a fixed support, said oscillatable member engaging said strip adjacent the knee of said S-shaped bend, said oscillatable member being adapted on energization of said electromagnetic means to open said circuit at said contacts only after hav-

ing stored up a predetermined amount of energy, and to thereafter maintain said contacts open until said energy is substantially spent after having performed a plurality of oscillations.

3. An improved contact device comprising in combination, an electromagnetic means having an iron core, an oscillatable member forming an armature of said means, said core having an air gap for deflecting the magnetic lines of force in the vicinity thereof, an oscillatably mounted contact, a second contact co-operating therewith, circuit means, and a circuit cut-off means in the form of a spring metal strip having an S-shaped bend, said cut-off means being located opposite said air gap and said bend having a knee thereof engaging said core, said oscillatable member engaging said strip adjacent the knee of said S-shaped bend, said oscillatable member being adapted on energization of said electromagnetic means to open said circuit at said contacts only after having stored up a predetermined amount of energy, and to thereafter maintain said contacts open until said energy is substantially spent after having performed a plurality of oscillations.

4. An improved contact device comprising in combination, an oscillatable member, electromagnetic means for periodically actuating said member, a pendulum member, a contact mounted on said pendulum member, a second contact cooperating therewith, circuit means, and a circuit cut-off means comprising a spring metal strip carrying said second contact at one end thereof, said strip having an S-shaped bend therein at a position opposite said oscillating member, said oscillatable member engaging said strip adjacent the knee of said S-shaped bend, said bend having a portion thereof engaging the core of said electromagnetic means, said oscillatable member having a natural frequency of vibration which is greater than the natural frequency of vibration of the contact carrying pendulum member and being adapted during each period of its movement to actuate said contact members in such a manner that the oscillatable member, once set in motion, will act to open said contacts only after having stored up a predetermined amount of energy, and to thereafter maintain said contacts open until said energy stored up in said member is substantially consumed after having performed a plurality of oscillations.

5. In an improved contact device of the type comprising an electromagnet actuator having an iron core and a winding, an air gap in the core, a straight pendulum arm secured to said iron core, a contact adjacent the free end of said arm and mounted thereon, a spring strip secured to said iron core, a contact adjacent the free end of said spring strip and mounted thereon in a position to coact with said contact on said pendulum arm, said contacts being biased to contacting position, said spring strip having an S-shaped bend therein adjacent the air gap in the iron core, an oscillatable pendulum arm secured to said core intermediate said straight pendulum arm and said spring strip and insulated therefrom, and a soft iron bob on the free end of said oscillatable pendulum arm adjacent said bend in said spring strip and said air gap, said oscillatable pendulum arm having a natural frequency of vibration which is greater than the natural frequency of vibration of the said straight pendulum arm, and comprising an armature for said electromagnet and being actuatable thereby, whereby upon energization of said electromagnet said oscillatable pendulum arm will be actuated

and serve to separate said contacts by striking said spring strip and said straight pendulum arm and to keep said contacts open during the period of oscillation of said oscillatable arm.
